UNITED STATES PATENT OFFICE.

THOMAS CANTWELL, OF BROOKLYN, ASSIGNOR, BY DIRECT AND MESNE ASSIGNMENTS, TO THE NIGHTINGALE FLOOR COMPANY, OF NEW YORK, N. Y.

FLOORING.

SPECIFICATION forming part of Letters Patent No. 412,946, dated October 15, 1889.

Application filed December 17, 1888. Serial No. 293,852. (No model.)

To all whom it may concern:

Be it known that I, THOMAS CANTWELL, of Brooklyn, in the county of Kings and State of New York, have invented new and useful 5 Improvements in Flooring, of which the following is a full, clear, and exact description.

This invention relates to flooring, the object of the invention being to provide for the quick and easy laying of wooden facing strips 10 or blocks upon concrete floors—such as are used in fire-proof buildings—in a manner such that the strips or blocks will be rigidly and firmly held to place.

To the end named the invention consists, essentially, of a series of longitudinally-slotted tubes arranged for connection with the base or body of the floor, a series of tie-bars arranged for connection with the facing strips or blocks, and fastening devices which pass 20 through the tie-bars and engage the slotted tubes.

Although the flooring to be hereinafter described is more especially designed for use upon a concrete floor, still the flooring could 25 be used upon any ordinary floor.

Reference is to be had to the accompanying drawings, forming a part of this specification, in which similar figures and letters of reference indicate corresponding parts in all 30 the views.

Figure 1 is a sectional view of my improved flooring, the view being taken on line *w w* of Fig. 2. Fig. 2 is a plan view of a section of the flooring, parts being broken away. Fig. 35 3 is a sectional view on line *x x* of Fig. 2. Fig. 4 is a plan view of a modified construction. Fig. 5 is a sectional view on line *y y* of Fig. 4; and Fig. 6 is a sectional view on line *z z* of Fig. 4, parts being broken away.

40 In laying the flooring forming the subject-matter of this application, I provide a number of tubes 10, formed with longitudinal slots 11. The tubes 10 are spaced and connected by strips 12, that are riveted to the tubes, as best shown in Fig. 1, rivets 13 being passed through the strips and through the tubes, as shown in the figure referred to. In addition to the strips 12, I connect anchor-

50 plates 14 to the tubes, said anchor-plates being arranged between the strips. The tubes 10 are of proper length to extend from side to side of the apartment, and the structure, made up as above described, is placed upon the floor. The space between the tubes is then filled with cement, these filled spaces 55 being shown at 16, and above the cement I place a layer of any proper material 17, such material being impervious to moisture. After the tubes 10 have been laid as above described a series of properly-united facing strips or 60 blocks, which form a floor-section A, each section being formed with longitudinal side slots *a*, is placed in position so as to extend at right angles to the tubes 10.

In the grooves *a* of the floor-sections A 65 there are placed tie-bars 20, which carry bolts 21, the shanks of said bolts extending through the slots 11 to engage nuts 22, which nuts are passed within the tubes through apertures 23, said apertures being located in any convenient position. After the floor-sections A have been adjusted to the required position 70 the bolts 21 are tightened by means of a screw-driver, which is brought into engagement with a nick formed in the head of each 75 bolt, the nuts being held from turning owing to the fact that they will bind against the inner walls of the tube. It will be noticed that the apertures through which the bolts 21 pass are at one side of the tie bars or strips 20. 80 After the first floor-section A has been secured to place the second floor-section is adjusted so that it will abut against the first floor-section and secured to place in the manner above described, that edge of the second floor-section 85 adjacent to the first floor-section engaging the strip 20 of the first series. Instead of having the strip 20 of metal, (such as is shown at 20^a in Figs. 1, 2, and 3,) the strip might be made of wood, as shown in Figs. 4, 90 5, and 6. In this case the strip would be shouldered to rest upon a shoulder *b*, formed at the edge of each floor-section of facing strips or blocks, and after the flooring has been laid the apertures within which the bolt-heads 95 rested would be plugged.

Such a flooring as the one above described may be readily laid, and when laid will be held firmly to the main floor.

Having thus described my invention, I claim

5

as new and desire to secure by Letters Patent—

1. The combination, with a series of longitudinally-slotted tubes, of a series of floor-sections, tie-bars or retaining-strips bearing

10 on shoulders formed at the edges of said floor-

sections, and fastening devices which connect

the tie-bars and the tubes, substantially as

described.

2. The combination, with a series of longi-

15 tudinally-slotted tubes, of uniting-strips 12,

connected to the tubes, floor-sections having

shoulders, tie-bars or retaining-strips which

rest upon said shoulders, bolts passing through

the tie-bars or retaining-strips and the slots

20 of the tubes, and nuts arranged within the

tubes, which nuts the bolts engage, substan-

tially as described.

3. The combination, with a series of spaced and longitudinally-slotted tubes having enlarged apertures 23, of floor-sections, tie-bars 25

or retaining-strips which engage shoulders

formed on the floor-sections, and bolts pass-

ing through the retaining-strips and the slots

of the tubes to engage nuts arranged within

the tubes, substantially as described.

4. In an attaching device for floors, the combination, with a series of longitudinally-

slotted tubes, of bars by which said tubes are

connected and spaced, anchor-plates con-

nected to the tubes, and bolts 21, which ex-

30 tend through the tube-slots, substantially as

described.

THOMAS CANTWELL.
